US0D1005934S

(12) **United States Design Patent** (10) **Patent No.:** **US D1,005,934 S**
Dunn (45) **Date of Patent:** **** Nov. 28, 2023**

(54) **COMBINED SOLAR POWERED
ELECTRONIC DISPLAY ASSEMBLY WITH
CHARGING STATION**

(71) Applicant: **Manufacturing Resources
International, Inc.**, Alpharetta, GA
(US)

(72) Inventor: **William Dunn**, Alpharetta, GA (US)

(73) Assignee: **Manufacturing Resources
International, Inc.**, Alpharetta, GA
(US)

(**) Term: **15 Years**

(21) Appl. No.: **29/895,035**

(22) Filed: **Jun. 16, 2023**

(56)

(57) **CLAIM**

The ornamental design for a combined solar powered electronic display assembly with charging station, as shown and described.

DESCRIPTION

FIG. 1 is a front perspective view of a combined solar powered electronic display assembly with charging station; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; and, FIG. 8 is a rear perspective view thereof.

The broken lines shown represent the portions of the combined solar powered electronic display assembly with charging station that form no part of the claimed design.
